UNITED STATES PATENT OFFICE

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY

LASTING MACHINE

Application August 15, 1927. Serial No. 212,999.

This invention relates to lasting machines for use in the manufacture of boots and shoes, and more particularly to end-lasting mechanism, the invention being herein illustrated in its application to means for lasting the toe ends of shoes, although in its more general aspects it is not limited to toe-lasting means. An important object is to provide improved means for lasting shoes of a type in which the upper is fastened to the insole in the lasting operation by cement, commonly known as tennis shoes or sneakers; and the invention is herein shown as applied to a tennis shoe lasting machine of the same general character as disclosed in my earlier application Serial No. 58,944, filed on September 26, 1925. It is to be understood, however, that the invention is not limited in utility to means for lasting shoes of that particular type nor to a machine organization of the particular character illustrated in that application.

In lasting the margin of an upper over an insole by the use of wipers in wiping engagement with the upper it is important that the insole be so positioned in relation to the bottom of the last and so controlled that no portion of it will be wrinkled or otherwise displaced by the inward wiping action of the wipers. Precautions against such displacement of the insole are especially necessary in lasting tennis shoes, since in shoes of that type it is customary to use insoles of rubber composition which are comparatively soft and pliable and which are not molded to the contour of the bottom of the last nor fastened to the last prior to the lasting operation. The present invention accordingly provides a novel organization of end-lasting wipers and means for insuring that portions of the insole otherwise liable to be displaced by the action of the wipers will not be so displaced. The invention is more particularly concerned with conditions at the sides of that end portion of the shoe where the wipers operate, and for the purposes in view the construction shown comprises novel means for laying or folding the margin of the upper inwardly over the insole without substantial wiping effect thereon, and for thereby press-

ing the margin of the insole down upon the bottom of the last, in locations substantially at the ends of the wipers, i. e., at those portions of the wipers that are farthest from the end face of the shoe. Preferably this overlaying or folding means is arranged to begin its overlaying action before the portions of the wipers adjacent thereto begin to wipe the upper inwardly over the insole, thus insuring that portions of the insole along the sides of the end portion of the shoe will not be so positioned as to be displaced by the wiping action of the wipers. The novel construction herein illustrated for accomplishing the objects in view comprises flexible lasting straps connected to the ends of the wipers and operated thereby to lay the upper over the insole, the straps being so disposed in relation to adjacent portions of the edges of the wipers as to begin their overlaying action before the wipers begin to wipe the upper inwardly at the sides of the end portion of the shoe. The construction shown further comprises means for rendering the lasting straps effective to wipe the upper heightwise of the last, i. e., to perform an "upwiping" operation thereon, prior to their overlaying action.

The invention will now be more particularly described by reference to the accompanying drawings and thereafter pointed out in the claims.

In the drawings,

Fig. 1 is a plan view of toe-lasting mechanism of the same general character as that disclosed in my earlier application, with the present invention embodied therein, a portion of the structure being broken away to show underlying parts more clearly;

Fig. 2 is a view in end elevation of the mechanism shown in Fig. 1, with parts in section;

Fig. 3 is a view similar to a portion of Fig. 2, illustrating the positions of the parts at the end of the toe-lasting operation;

Fig. 4 is a plan view illustrating the positions of the parts at an earlier stage in the lasting operation; and

Fig. 5 is a view in elevation, further illustrating the action of the lasting straps at that time in the lasting operation indicated by Fig. 4.

55 60 65 70 75 80 85 90 95 100

Since the general organization and manner of operation of the machine to which the present invention is herein shown as applied are fully disclosed in the earlier application, only 5 such parts of the machine as it is necessary to refer to for an understanding of the invention will be described in detail. It will be understood that the last with shoe materials comprising an insole *a* and an upper *b* thereon is mounted on a shoe support (not shown) with its toe end portion positioned upon a toe rest 10 which has a depending hollow stem 12 slidably mounted in a holder 14. The toe rest 10 is depressible by the shoe against the 10 resistance of a spring 16 within the hollow stem 12, an additional spring 18 being provided at the lower end of the hollow stem to be engaged and compressed by the latter near the end of the downward movement of the toe rest. The depression of the shoe and the toe rest is effected by means including a presser foot 20 which engages the insole centrally at the toe end of the last, and as the shoe is forced downwardly the upper about the toe of the 15 last is engaged and wiped upwardly toward the edge of the insole by a yieldable toe band 22 which embraces the toe end of the shoe. The presser foot 20 assists in holding the insole in proper position on the last, and in addition to the presser foot, there is provided a curved member 23 which engages the margin of the insole about the end portion of the toe and presses it closely against the bottom of the last to prevent its displacement in that location in the overwiping operation.

After the shoe has arrived at the end of its downward movement, the margin of the upper about the end and along the sides of the toe is gathered and wiped inwardly over the insole by toe-lasting wipers which, in the construction shown, comprise a pair of end wiper plates 24 having wiping edges curved to embrace the upper about the end portion of the toe and a pair of side wiper plates 26 which are arranged to act only at the sides of the toe. The wipers 24 are mounted for movements in a curved guideway 28 about an axis extending heightwise of the shoe and located centrally of the toe, the guideway 28 being 40 formed in a wiper carrier 30 mounted for movement lengthwise of the shoe in a holder or casing 32. The wiper plates 24 thus have advancing movement lengthwise of the shoe and closing movements laterally of the shoe. 45 The side wiper plates 26, on the other hand, are mounted for swinging or closing movements laterally of the shoe without advancing movement, being pivoted at 34 on the casing 32 to swing about axes extending heightwise of the shoe. The wiper plates 26 have comparatively thin edges arranged to underlie the plates 24, and the latter in their operative movement advance over the upper or outer faces of the plates 26.

Advancing movement lengthwise of the

shoe is imparted to the wiper plates 24 by means of a rock shaft 36 in the casing 32, this rock shaft being connected to the wiper carrier 30 to move it forwardly by mechanism not shown in detail but fully disclosed in the earlier application. For imparting swinging or closing movements to these wiper plates, there are provided gear sectors 38 which are pivotally mounted on the casing 32 and are connected by links 40 to the wipers 24. Each of the gear sectors 38 is operated by a rack member 42 to which operative movement is imparted by the rock shaft 36 through connections also more fully disclosed in the earlier application. It will thus be seen that in the movement of the rock shaft 36 to advance the end wipers 24 the gear sectors 38 also are operated by the rock shaft to impart closing movements to these wipers. Closing movements are at the same time imparted to the side wipers 26 by the gear sectors 38 through rolls 44 which are mounted on the gear sectors and engage the outer edges of the wipers 26, the return movements of these wipers being effected by rolls (not shown) which are mounted on studs 46 that connect the links 40 to the wipers 24 and engage upraised portions 48 of the wiper members 26. Since the side wipers 26 move only in directions laterally of the shoe, the construction provided serves to avoid undue bending of the margin of the upper at the sides of the toe lengthwise of the shoe in the toe-lasting operation.

The construction thus far described is substantially like what is shown in the earlier application. For purposes of this invention there are provided at the rear ends of the toe-lasting wipers flexible lasting straps 50 which, in the construction shown, are connected to the side wiper plates 26 and are operated thereby to lay or fold the margin of the upper inwardly over the insole without any substantial wiping action thereon and through the upper to press the margin of the insole in those locations upon the bottom of the last, the arrangement being such that the straps begin their overlaying and pressing action before the wipers 26 adjacent to the straps begin to wipe the upper inwardly over the insole, as will be evident by reference to Fig. 4. The straps 50, which may be made of leather or other suitable material, are controlled by upraised portions 52 on the ends of the wiper members 26 and are received in recesses 54 in these members as the latter are moved inwardly toward the shoe. As their upper ends the straps are connected to slides 56 which are mounted for movements laterally of the shoe in the upraised portions 52 of the wipers 26, and controlling these slides are springs 58 which yield in the overwiping operation of the wipers to permit the wipers 26 to move relatively to the straps.

To assist in preventing the straps 50 from

having any overwiping action at the time of the operative movement of the wipers, they are fastened at their lower ends to holders 60 by the action of which they are pressed 5 against the sides of the shoe. These holders are pivotally mounted at 62 on the upper ends of carriers 64 provided with depending shanks 66 which are swiveled in arms 68 for movement about axes extending heightwise of the shoe to permit the holders 60 to adapt themselves to the contour of the shoe. The arms 68 are pivoted at 70 on plates 72 which are secured to a stationary bracket 74. A spring 76 connected to the opposite arms 15 68 tends to swing these arms and the lower ends of the straps 50 toward each other as far as permitted by stop screws 78 which are threaded in the arms 68 and are arranged to engage the plates 72, these stop screws being 25 adjustable to adapt the straps to shoes of different widths.

By reference to Fig. 2 it will be seen that, as the parts are initially positioned, the lower ends of the straps 50 and their holders 60 underlie the side portions of the shoe in the path of the downward movement of the shoe when the latter is depressed. Accordingly, in the downward movement of the shoe, the straps 50 serve to wipe the upper upwardly toward the edge of the insole and thus to tighten it over the last across the forepart, simultaneously with the upward wiping action of the toe band 22 in front of the straps. In this upwiping action of the straps their holders 25 60 are spread apart against resistance of the spring 76, as will be evident by reference to Fig. 3, and thereafter the straps are pressed by their holders against the sides of the shoe to hold the upper in its upwiped condition, 40 while they are held against overwiping action on the upper in the operative movement of the wipers.

It will be understood that at the time of the overwiping movement of the wipers the 45 shoe is maintained by its depressing means, including the presser foot 20, in a position in which the insole is spaced somewhat beneath the lower faces of the wipers, to assist further in avoiding displacement of any portion 50 of the margin of the insole in the overwiping operation, as will be evident by reference to Fig. 5, and that after the wipers have completed their overwiping movement the shoe is pressed upwardly in response to retractive 55 movement of the depressing means to cause the wipers to press the cement-coated margin of the upper firmly upon the bottom face of the insole, as fully disclosed in the earlier application. The recesses 54 in which the 60 straps 50 are received extend inwardly under the wiper members 26, as shown in Figs. 2 and 3, and are so arranged that at the end of the overwiping operation the lower faces of these wiper members and the faces of the 65 straps which are in engagement with the over-

laid margin of the upper are substantially in the same plane, so that the faces of the wipers and of the straps are both effective to press the upper firmly against the insole in the upward movement of the shoe toward the wipers. It will be further seen, by reference to Fig. 1, that portions of the straps 50 which are secured to the holders 60 are wider than portions engaged by the wiper members 26, so that these widened portions serve to upwipe the upper in locations underneath portions of the margin of the upper that are engaged by the edges of the wipers 26, these widened portions of the straps serving virtually as extensions of the toe band 22.

In the operation of the toe-lasting means, briefly summarized, the last with the upper and the insole thereon is forced downwardly by the action of the shoe-depressing means, including the presser foot 20, at a predetermined time in the cycle of the machine as a whole, as more fully disclosed in the earlier application. In this downward movement of the shoe the toe rest 10 is depressed against the resistance of its spring 16, and finally against the added resistance of the supplemental spring 18, and the toe band 22 and the lasting straps 50 serve to wipe the upper upwardly toward the edge of the insole, the strap holders 60 being swung apart against the resistance of the spring 76 by wedging action of the shoe thereon. Thereafter the toe-lasting wipers 24 and 26 are operated by the rock shaft 36 to wipe the upper about the toe inwardly over the insole, the side wipers 26 receiving only swinging movements laterally of the shoe, while the end wipers 24 are both advanced lengthwise of the shoe and swung inwardly, portions of these wipers advancing over the upper faces of the wipers 26. As the side wipers 26 receive their inward swinging movements, they carry the straps 50 inwardly over the margin of the insole, 100

without any wiping action on the upper, but with a folding action whereby they bend the margin of the upper inwardly over the edge of the insole and act through the upper to insure that the margin of the insole at the rear ends of the wipers will be pressed down upon the bottom of the last without objectionable inward displacement from the edge of the last bottom. Since the straps are so positioned relatively to the edges of the wipers 26 that they being their overlaying and pressing action before the wipers begin to wipe the upper inwardly at the sides of the toe, as indicated by Figs. 4 and 5, insurance is afforded that portions of the margin of the insole at the sides of the toe at the rear of the member 23 will not be in position to be displaced by the wipers. During the overwiping action of the wipers the straps are carried farther inwardly over the insole, the slides 56 being pulled inwardly along their guideways, and thereafter the shoe is pressed 110 115 120 125 130

upwardly against the wipers and the straps by the action of means including the springs 16 and 18 to cement the margin of the upper firmly to the insole.

5 Having described the invention, what I claim as new and desire to secure by Letters Patent of the United States is:—

10 1. In a machine of the class described, toe-lasting wipers for wiping an upper inwardly over an insole about the end and along the sides of the toe of a shoe, and means for laying the upper over the insole without substantial wiping effect thereon in locations substantially at the rear ends of said wipers, said means being arranged to begin its overlaying action on the upper before the wipers begin to wipe the upper inwardly at the sides of the toe and to operate progressively on the upper during the operation of the wipers.

20 2. In a machine of the class described, toe-lasting wipers for wiping an upper inwardly over an insole about the end and along the sides of the toe of a shoe, and means operative in automatically determined time relation to the wipers for laying the upper over the insole without substantial wiping effect thereon and for pressing the insole upon the bottom of the last in locations substantially at the rear ends of said wipers, said means being so controlled as to begin its overlaying and pressing action before the wipers begin to wipe the upper inwardly at the sides of the toe.

30 3. In a machine of the class described, toe-lasting wipers for wiping an upper inwardly over an insole about the end and along the sides of the toe of a shoe, and flexible upper-engaging means for laying the upper over the insole without substantial wiping effect thereon and for pressing the insole upon the bottom of the last in locations substantially at the rear ends of said wipers, said means being arranged to begin its overlaying and pressing action in automatically determined time relation to the operation of the wipers before the wipers begin to wipe the upper inwardly at the sides of the toe.

40 4. In a machine of the class described, toe-lasting wipers for wiping an upper inwardly over an insole about the end and along the sides of the toe of a shoe, and means comprising flexible straps arranged to fold the upper over the insole and to press the insole upon the bottom of the last in locations substantially at the rear ends of said wipers, said straps being so controlled as to begin their folding and pressing action in automatically determined time relation to the operation of the wipers before the wipers begin to wipe the upper inwardly at the sides of the toe.

50 5. In a machine of the class described, end-lasting wipers for wiping an upper inwardly over an insole about an end and along the sides of the end portion of a shoe, and means relatively to which the wipers are movable

70 arranged to be operated by said wipers in that relative movement to lay the upper over the insole without substantial wiping effect thereon in locations substantially at the ends of the wipers in predetermined time relation to the wiping action of the wipers on the upper in other locations.

75 6. In a machine of the class described, end-lasting wipers for wiping an upper inwardly over an insole about an end and along the sides of the end portion of a shoe, and flexible lasting straps arranged to be operated by said wipers to lay the upper over the insole and to press the insole upon the bottom of the last only in locations substantially at the ends of said wipers.

80 7. In a machine of the class described, end-lasting wipers for wiping an upper inwardly over an insole about an end and along the sides of the end portion of a shoe, and flexible means arranged to be operated by said wipers to lay the upper over the insole without substantial wiping effect thereon and to press the insole upon the bottom of the last in locations substantially at the ends of the wipers and to begin its overlaying and pressing action before the wipers begin to wipe the upper inwardly at the sides of the shoe.

85 8. In a machine of the class described, end-lasting wipers for wiping an upper inwardly over an insole about an end and along the sides of the end portion of a shoe, and flexible lasting straps connected to said wipers and arranged to lay the upper inwardly over the insole only in locations substantially at the ends of the wipers in response to operative movement of the wipers.

90 9. In a machine of the class described, end-lasting wipers for wiping an upper inwardly over an insole about an end and along the sides of the end portion of a shoe, flexible lasting straps arranged to be operated by said wipers to lay the upper over the insole in locations substantially at the ends of said wipers, and spring means carried by said wipers for controlling the straps, said spring means being yieldable in response to pull of the straps thereon in the operative movement of the wipers.

95 10. In a machine of the class described, end-lasting wipers for wiping an upper inwardly over an insole about an end and along the sides of the end portion of a shoe, flexible lasting straps arranged to be operated by said wipers to lay the upper over the insole in locations substantially at the ends of said wipers, members connected to said straps and slidably mounted on said wipers for movement laterally of the shoe in response to pull of the straps thereon in the operation of the wipers, and springs against the resistance of which said members are thus movable.

11. In a machine of the class described, end-lasting wipers for wiping an upper inwardly over an insole about an end and along the

- sides of the end portion of a shoe, flexible lasting straps arranged to be operated by said wipers to lay the upper over the insole in locations substantially at the ends of said wipers in predetermined time relation to the wiping action of the wipers on the upper in other locations, means for pressing said straps against the sides of the shoe, and connections between said straps and the wipers arranged to yield in response to pull of the straps thereon in the operation of the wipers. 12. In a machine of the class described, toe-lasting wipers for wiping an upper inwardly over an insole about the end and along the sides of the toe of a shoe, and means operative in automatically determined time relation to said wipers to wipe the upper heightwise of the shoe in locations substantially at the rear ends of said wipers and then to begin to lay the upper over the insole without substantial wiping effect thereon and to press the margin of the insole upon the bottom of the last in those locations before the wipers begin to wipe the upper inwardly at the sides of the toe. 13. In a machine of the class described, toe-lasting wipers for wiping an upper inwardly over an insole about the end and along the sides of the toe of a shoe, flexible lasting straps arranged to be operated by said wipers to lay the upper over the insole and to press the insole upon the bottom of the last in locations substantially at the rear ends of said wipers in predetermined time relation to the wiping action of the wipers on the upper in other locations, and means for effecting relative movement of said straps and the shoe to wipe the upper heightwise of the shoe prior to the operation of the wipers. 14. In a machine of the class described, toe-lasting wipers for wiping an upper inwardly over an insole about the end and along the sides of the toe of a shoe, flexible lasting straps arranged to be operated by said wipers to lay the upper over the insole in locations substantially at the rear ends of the wipers in predetermined time relation to the wiping action of the wipers on the upper in other locations, means for depressing the shoe relatively to the wipers, and means for pressing said lasting straps against the sides of the shoe to cause them to upwipe the upper in response to depression of the shoe. 15. In a machine of the class described, toe-lasting wipers for wiping an upper inwardly over an insole about the end and along the sides of the toe of a shoe, flexible lasting straps arranged to be operated by said wipers to lay the upper over the insole in locations substantially at the rear ends of the wipers in predetermined time relation to the wiping action of the wipers on the upper in other locations, means for depressing the shoe relatively to the wipers, and spring-controlled members connected to said lasting straps and arranged to be spread apart by the depression of the shoe while holding the straps against the sides of the shoe to cause them to upwipe the upper. 16. In a machine of the class described, end-lasting wipers mounted to swing laterally of a shoe each about an axis extending heightwise of the shoe to wipe the upper at an end portion of the shoe inwardly over the insole, and flexible lasting straps arranged to be operated by said wipers to lay the upper inwardly over the insole without substantial wiping effect thereon in predetermined locations in time relation to the wiping action of the wipers on the upper in other locations. 17. In a machine of the class described, end-lasting wipers mounted to swing laterally of a shoe each about an axis extending heightwise of the shoe to wipe the upper at an end portion of the shoe inwardly over the insole, flexible lasting straps arranged to be operated by said wipers to lay the upper inwardly over the insole in predetermined locations, and spring means connecting said straps to the wipers and yieldable in response to pull of the straps thereon in the operation of the wipers. 18. In a machine of the class described, end-lasting wipers comprising end wiper plates for wiping an upper inwardly over an insole about an end of a shoe and side wiper plates for wiping the upper inwardly at the sides of the end portion of the shoe beyond said end plates, the end and side plates being mounted for operative swinging movement each about an axis extending heightwise of the shoe, and flexible lasting straps arranged to be operated only by the side plates to lay the upper inwardly over the insole without substantial wiping effect thereon. In testimony whereof I have signed my name to this specification. BERNHARDT JORGENSEN. 110 115 120 125 130
